E. CAIRNS

HEADGEAR

Filed Feb. 26, 1925

BY

INVENTOR:
Edward Cairns,
McMurrayton,

His ATTORNEY.

UNITED STATES PATENT OFFICE.

EDWARD CAIRNS, OF MONTCLAIR, NEW JERSEY.

HEADGEAR.

Application filed February 28, 1925. Serial No. 11,736.

To all whom it may concern:

Be it known that I, EDWARD CAIRNS, a citizen of the United States, and a resident of Montclair, in the county of Essex and

5 State of New Jersey, have invented new and useful Improvements in Headgears, of which the following is a specification.

This invention relates to improvements in head gear being especially adapted for firemen's helmets, although being applicable to other types of hats and has for its particular objects the provision of an insert device which is not only cheap and durable, but which is adapted to securely retain a hat on 10 the head of the wearer and prevent accidental displacement thereof while also serving to cause the hat to conform closely to the shape of the head of the wearer and substantially reduce the number of sizes which 15 20 25

a dealer is required to carry in stock in order to enable many different sizes of heads to be properly fitted. Such device is also extremely comfortable to wear and can be readily applied to an ordinary hat without requiring any alteration in the shape or construction thereof.

My invention is fully described in the following description and drawings forming a part thereof in which—

30 Figure 1 is a vertical longitudinal section of a fireman's helmet equipped with one of my improved inserts;

Fig. 2 is a perspective view of the aforesaid insert isolated;

35 Fig. 3 is a vertical fragmentary section of a portion of the helmet and of the insert and its cushioning adapter, showing the same when removed from the head of the wearer; Fig. 4 is a similar view showing the position assumed by the insert and its marginal cushioning member with respect to the helmet when the latter is applied to the head of the wearer; Fig. 5 is a similar view showing the position assumed by the insert and 40 45 50

its marginal cushioning member with respect to the helmet when it is attempted to shake the same off or remove the same from the head of a wearer; and

Fig. 6 is a perspective fragmentary view 55 of a portion of said cushioning member.

Referring to the drawings and the construction shown therein, reference numeral 1 designates the body member and 2 the brim member of a fireman's helmet. At the 55 point of intersection of said body member and said brim member is formed an annular

groove 3 into which latter is adapted to be sprung the expandible reinforced lower rim of an insert member hereinafter described.

The aforesaid insert member comprises 60 an elastic hoop or ring member 4, formed preferably of a continuous piece of spring wire which is secured within a covering 5 of leather or the like and to which latter is secured a sectional lining composed of sections of felt 6, 6' and which latter are shaped to conform substantially to the curvature of the head of the wearer but which are joined at the top in such a manner as to leave an opening of insufficient size to permit the 70 skull of the wearer to pass completely therethrough. However, no particular claim is made herein to the insert of the above construction as the same forms no part of the 75 invention herein described.

The essence of the herein described invention comprises the association with the aforesaid insert of an elastic cushioning medium 7 preferably comprising a narrow strip of sponge rubber which is securely 80 stitched at its lower edge to the outside of said insert immediately above the covering 5 which surrounds the elastic wire ring 4 in such a manner that the lower edge or margin *a* of said cushioning medium is 85 slightly stretched so as to form a ring of greater perimeter than the ring formed by its upper edge or margin *b*. As a consequence, the said cushioning means will normally assume a position of about 45° to 60° 90 with respect to the horizontal, for example, as shown in Figure 2. When however, the said hat provided with the aforesaid improved insert is applied to the head of the wearer, the cushioning medium or adapter 95 will be forced into the position shown in Fig. 4, but as soon as it is attempted to remove the hat or the same tends to move off the head of the wearer due to the weight thereof, the said elastic cushioning medium 100 assumes the position shown in Fig. 5 and tightly wedges the insert or lining on to the head of the wearer, thus effectually preventing accidental displacement or easy removal of the hat, except when such removal 105 is desired, in which latter case by exerting a sufficient pressure the hat can be readily removed. In practice I prefer a strip of sponge or cellular rubber of the quality 110 commonly used in rubber bath sponges, rubber applicators for electric massage machines and the like and such strips should

not exceed $\frac{1}{2}$ " in thickness, preferably being about $\frac{5}{8}$ " in height and $\frac{1}{16}$ " in thickness.

6 The aforesaid adapter is exceedingly soft and readily conforms to the irregular contour of the different heads to which it may be desired to apply the same. Furthermore, said adapter does not shrink nor otherwise change in size or shape when drenched 10 with water and should the felt insert become wet it can be dried out without deleteriously affecting the adapter member.

15 Various modifications of form, size and in the minor details of construction within the scope of the appended claims may be made without departing from the spirit of my invention or dispensing with the various advantages peculiar to the invention herein set forth.

20 Having thus described my invention, what I claim and desire to obtain by United States Letters Patent is:

1. The combination comprising a hat body 25 of relatively inelastic material, an insert lining therefor adapted to engage the skull of a wearer, an annular elastic cushioning member of sponge rubber secured to the insert lining adjacent the lower margin thereof, said cushioning member having normally a 30 smaller outer periphery when unstretched than the inner periphery of the hat body to which it is secured so that the lower

margin of said cushioning member is stretched with respect to its upper margin and said cushioning member being so positioned that it normally assumes an oblique angle with respect to the sides of the hat prior to its being placed on the head of the wearer. 35

2. The combination comprising a hat 40 body of relatively inelastic material, an insert lining therefor adapted to engage the skull of a wearer and an elastic cushioning adapter member of sponge rubber secured to said insert member adjacent its lower margin 45 and interposed between said insert member and said hat body, said adapter member normally lying at an oblique angle to the sides of the hat.

3. The sub-combination comprising an 50 insert lining for a hat having an annular cushioning adapter member of porous sponge rubber secured to its outer face adjacent the lower margin thereof, said cushioning member having normally a smaller outer 55 periphery when unstretched than the inner periphery of the hat body to which it is to be secured so that the lower edge of said adapted will be stretched relatively to its upper edge. 60

Signed at New York, in the county and State of New York this 25th day of February 1925.

EDWARD CAIRNS.

not exceed $\frac{1}{2}$ " in thickness, preferably being about $\frac{5}{8}$ " in height and $\frac{1}{16}$ " in thickness.

The aforesaid adapter is exceedingly soft and readily conforms to the irregular contour of the different heads to which it may be desired to apply the same. Furthermore, said adapter does not shrink nor otherwise change in size or shape when drenched with water and should the felt insert become wet it can be dried out without deleteriously affecting the adapter member.

Various modifications of form, size and in the minor details of construction within the scope of the appended claims may be made without departing from the spirit of my invention or dispensing with the various advantages peculiar to the invention herein set forth.

Having thus described my invention, what I claim and desire to obtain by United States Letters Patent is:

1. The combination comprising a hat body of relatively inelastic material, an insert lining therefor adapted to engage the skull of a wearer, an annular elastic cushioning member of sponge rubber secured to the insert lining adjacent the lower margin thereof, said cushioning member having normally a smaller outer periphery when unstretched than the inner periphery of the hat body to which it is secured so that the lower

margin of said cushioning member is stretched with respect to its upper margin and said cushioning member being so positioned that it normally assumes an oblique angle with respect to the sides of the hat prior to its being placed on the head of the wearer. 35

2. The combination comprising a hat body of relatively inelastic material, an insert lining therefor adapted to engage the skull of a wearer and an elastic cushioning adapter member of sponge rubber secured to said insert member adjacent its lower margin and interposed between said insert member and said hat body, said adapter member normally lying at an oblique angle to the sides of the hat. 45

3. The sub-combination comprising an insert lining for a hat having an annular cushioning adapter member of porous sponge rubber secured to its outer face adjacent the lower margin thereof, said cushioning member having normally a smaller outer 55 periphery when unstretched than the inner periphery of the hat body to which it is to be secured so that the lower edge of said adapted will be stretched relatively to its upper edge. 60

Signed at New York, in the county and State of New York this 25th day of February 1925.

EDWARD CAIRNS.

Certificate of Correction.

It is hereby certified that in Letters Patent No. 1,575,251, granted March 2, 1926, upon the application of Edward Cairns, of Montclair, New Jersey, for an improvement in "Headgears," an error appears in the printed specification requiring correction as follows: Page 2, line 59, claim 3, for the word "adapted" read *adapter*; and that the said Letters Patent should be read with this correction therein that the same may conform to the record of the case in the Patent Office.

Signed and sealed this 27th day of April, A. D. 1926.

[SEAL.]

M. J. MOORE,
Acting Commissioner of Patents.

Certificate of Correction.
